(57) **CLAIM**

The ornamental design for a hair dryer pick attachment, as shown and described.

DESCRIPTION

FIG. 1 is a perspective view of a hair dryer pick attachment showing a new design;

FIG. 2 is a front elevational view thereof;

FIG. 3 is a rear elevational view thereof;

FIG. 4 is a left side elevational view thereof;

FIG. 5 is right side elevational view thereof;

FIG. 6 is a top plan view thereof;

FIG. 7 is a bottom plan view thereof;

FIG. 8 is another perspective view thereof;

FIG. 9 is an enlarged, left side elevational view of a portion of the hair dryer pick attachment of FIG. 4; and,

FIG. 10 is an enlarged, right side elevational view of a portion of the hair dryer pick attachment of FIG. 5.

The broken lines in the figures illustrate portions of the hair dryer pick attachment that form no part of the claimed design. The broken lines shown in FIGS. 4, 5, 9 and 10 depict the bounds of the enlarged views and form no part of the claimed design.

1 Claim, 8 Drawing Sheets
